TWO-CYCLE INTERNAL COMBUSTION
ENGINE

Charles S. Brown, Syracuse, N. Y.

Application August 27, 1942, Serial No. 456,374

6 Claims. (Cl. 123—65)

This invention relates to two cycle internal combustion engines, and has for its object an arrangement of the intake and exhaust ports, whereby a maximum amount of fuel mixture can, upon each stroke, be forced into the cylinder with a maximum amount of exploded mixture from the preceding cycle scavenged, so that there is a minimum of combusted charge left in the cylinder at the end of the scavenging stroke.

The invention consists in the novel features and in the combinations and constructions hereinafter set forth and claimed.

In describing this invention, reference is had to the accompanying drawings in which like characters designate corresponding parts in all the views.

Figure 1 is a vertical sectional view through one cylinder of an engine embodying this invention.

Figures 2 and 3 are opposite side elevations, Figure 2 being partly broken away.

Figure 4 is a sectional view on line 4—4, Figure 3.

Figure 5 is a sectional view on line 5—5, Figure 2.

1 designates the cylinder block, which is here shown as formed jacketed for liquid cooling, this being provided with a series of cylinder bores, as 2, in each of which works a power piston 3. 4 is a main crankshaft suitably mounted in a crank casting 5, and 6 is a connecting rod connecting each power piston 3, and a main crankshaft crank pin 4^a on the main crankshaft 4. The cylinder is also formed with a jacketed cylinder head 7. The cylinder head 7 is formed with a piston valve passage 8 therethrough in which works a piston valve 9, this being actuated by an overhead piston valve eccentric shaft 10 having eccentrics 11 thereon embraced by eccentric straps 12 having eccentric rods as 13 pivoted with the piston valve pin 14 to the piston valve 9. The piston valve eccentric shaft 10 is suitably mounted in an eccentric shaft casing 15 mounted on the cylinder head 7.

16 designates an intake charge port, and 17 an auxiliary exhaust gas port, these being formed in the head of the cylinder and opening into the piston valve passage 8. They are here shown as opening into the piston valve passage 8 at diametrically opposite points, and as extending through sides of the cylinder head 7. These ports are so located that the intake charge port 16 is opened in advance of opening of the auxiliary exhaust gas port 17, and hence closed after the auxiliary exhaust gas port 17 is closed, and both being fully open at the same time. As here illustrated, the ports 16, 17 are arranged in axial alinement on 18

opposite sides of the piston valve passage 8 but the intake charge port 16 is of larger diameter than the auxiliary exhaust gas port 17.

18 designates main exhaust gas port located in position to be uncovered by the power piston 3, when at the end of its power stroke. In some types of engines, ports located as the main exhaust gas port 18 is located, are referred to as auxiliary gas exhausts. In this engine, however, the port 18 is the main exhaust gas port as compared with the capacity of the port 17 which, in this case, is the auxiliary exhaust gas port instead of the main exhaust gas port 18.

19 designates an intake charge manifold communicating with the intake charge port 16 of the cylinder block, this communicating with a carburetor 20 which may have an intake charge air cleaner 21 on its intake charge air intake. The fuel mixture is forced or supercharged into the intake charge manifold 19 and through the intake charge port 16 by any suitable means, here shown as located in the intake charge pipe 22 between the carburetor and the intake charge port 16. This supercharging means may be of any suitable construction, and the construction forms no part of this invention. It is here shown as an intake charge blower or supercharger 23 having its casing provided with a blower intake 24 and blower exhaust 25 connected to the sections of the intake charge pipe 22 respectively, and intermeshing gearlike elements, blower vane driver 26 and driven blower vane 27 in the casing, one gear element being mounted upon an extension, blower vane driver shaft 28, of the main crankshaft, or on another shaft actuated by the main crankshaft. The piston valve eccentric shaft 10 is actuated from the main crankshaft by a piston valve eccentric shaft drive chain 29 running over sprockets on the eccentric shaft and on the main crankshaft.

30 designates the auxiliary exhaust gas manifold for the auxiliary exhaust gas port 17, and 31 is the main exhaust gas manifold for the main exhaust gas port 18. The auxiliary exhaust gas manifold 30 is connected to the main exhaust gas pipe 32 leading from one of the main exhaust gas manifolds 31 so that the exhaust gas from the auxiliary exhaust gas manifold 30 siphons into the main exhaust gas pipe 32 or is drawn out of the auxiliary exhaust gas manifold 30 into the main exhaust gas pipe 32 by the action of the exhaust gases from one of the main exhaust gas manifolds 31 acting through the main exhaust gas pipe 32. As here shown, an auxiliary exhaust gas pipe 33 leading from the auxiliary exhaust

gas manifold 30 extends into the main exhaust gas pipe 32 and is provided with an ejector nozzle, auxiliary exhaust gas Sylphon 34. This nozzle may be of the shape shown in Figure 5, which is an oval section having the same perimeter as that of the auxiliary exhaust gas pipe 33.

The piston valve is provided with a piston valve deflector 35 on its inner end located to deflect the incoming charge into the series of cylinder bores 2 in a direction opposite to the flow of the exhaust gases to the auxiliary exhaust gas port 17, so that the incoming combustible charge does not mix to an appreciable extent with the combusted charge exhausting out through the auxiliary exhaust gas port 17.

The compressed charge, which has entered the cylinder through the intake charge port 16, is ignited by a suitable electric ignition spark plug.

In operation, with the engine started, an explosive mixture is drawn through the carburetor 20 and, forced into the intake charge manifold 19 under the action of the intake charge blower or supercharger 23.

When the piston valve 9 uncovers the intake charge port 16 and slightly thereafter the auxiliary exhaust gas port 17, at which time the piston is at the end of its power stroke and has uncovered the main exhaust gas port, the charge passes under the pressure of the intake charge blower or supercharger 23 through the intake charge port 16 into the cylinder through the now open piston valve passage 8 and is directed by the piston valve deflector 35 inwardly. While the greater part of the exhaust gas has already passed out through the main exhaust gas port 18, the intake charge now forces the remaining exhaust gas out through the auxiliary exhaust gas port 17 being facilitated in its passage through the auxiliary exhaust gas port 17 by the incoming charge under pressure, and by the suction created in the main exhaust gas pipe 32 on the auxiliary exhaust gas Sylphon 34. The opening of the intake charge port 16 in advance of the closing of the main exhaust gas port 18 is the same as the advance given the openings of intake charge ports 16 on all modern gas engines over the exhaust gas ports to insure more complete charging of the cylinders with combustible ingredients.

What I claim is:

1. In a two cycle internal combustion engine including a cylinder, a piston in the cylinder, a crankshaft, and a connecting rod between the piston and the crankshaft; the combination of the head of the cylinder being formed with a valve passage, intake and auxiliary exhaust gas ports opening into said passage, and a piston valve arranged to open and close said ports, with both ports being open and closed at the same time, and with said ports arranged so that the intake port is opened before the auxiliary exhaust gas port and closed after the auxiliary exhaust gas port closes, the piston valve having a deflector located to deflect the incoming intake charge into the cylinder in a direction opposite to the path of the auxiliary exhaust gas to the auxiliary exhaust gas port, the cylinder also having main exhaust gas ports arranged to be opened when the piston approaches the end of its power stroke, and mechanism for supplying a motive vapor under pressure to the intake port and for operating the piston valve.

2. In a two cycle internal combustion engine including a cylinder, a piston in the cylinder, a crankshaft, and a connecting rod between the

piston and the crankshaft; the combination of the head of the cylinder being formed with a valve passage, intake and auxiliary exhaust gas ports opening into said passage, and a piston valve arranged to open and close said ports, with both ports being open and closed at the same time, and with said ports arranged so that the intake port is opened before the auxiliary exhaust gas port and closed after the auxiliary exhaust gas port closes, the piston valve having a deflector located to deflect the incoming intake charge into the cylinder in a direction opposite to the path of the auxiliary exhaust gas to the auxiliary exhaust gas port, the cylinder also having main exhaust gas ports arranged to be opened when the piston approaches the end of its power stroke, mechanism for supplying a motive vapor under pressure to the intake port and for operating the piston valve, and means to draw the auxiliary exhaust gas through the auxiliary exhaust gas port controlled by the piston valve.

3. In a two cycle internal combustion engine including a cylinder, a piston in the cylinder, a crankshaft, and a connecting rod between the piston and the crankshaft; the combination of the head of the cylinder being formed with a valve passage, intake and auxiliary exhaust ports opening into said passage, and a piston valve arranged to open and close said ports, with both ports being open and closed at the same time, and with said ports arranged so that the intake port is opened before the auxiliary exhaust gas port and closed after the auxiliary exhaust gas port closes, the piston valve having a deflector located to deflect the incoming intake charge into the cylinder in a direction opposite to the path of the auxiliary exhaust gas to the auxiliary exhaust gas port, the cylinder also having main exhaust gas ports arranged to be opened when the piston approaches the end of its power stroke, intake and exhaust manifolds, the auxiliary exhaust gas manifold for the auxiliary exhaust gas port in the head of the cylinder being connected to the main exhaust gas pipe and being provided with a nozzle in the main exhaust gas pipe operating to effect suction through the auxiliary exhaust gas port controlled by the piston valve, and means for operating the piston valve.

4. In a two cycle internal combustion engine including a cylinder, a piston in the cylinder, a crankshaft, and a connecting rod between the piston and the crankshaft; the combination of the head of the cylinder being formed with a valve passage, intake and exhaust ports opening into said passage, and a piston valve arranged to open and close said ports, and with said ports arranged so that the intake port is open before the auxiliary exhaust gas port and closed after the auxiliary exhaust gas port closes, the piston valve having a deflector located to deflect the incoming intake charge into the cylinder in a direction opposite to the path of the auxiliary exhaust gas to the auxiliary exhaust gas port, the cylinder also having main exhaust gas ports arranged to be opened when the piston approaches the end of its power stroke, means for operating the piston valve, and means for forcing a fuel vapor mixture through the intake port.

5. In a two cycle internal combustion engine including a cylinder, a piston in the cylinder, a crankshaft, and a connecting rod between the piston and the crankshaft; the combination of the head of the cylinder being formed with a valve passage, intake and auxiliary exhaust ports opening into said passage, and a piston valve ar-

ranged to open and close said ports, with both ports being open and closed at the same time, and with said ports arranged so that the intake port is open before the auxiliary exhaust gas port and closed after the auxiliary exhaust gas port closes, the piston valve having a deflector located to deflect the incoming charge into the cylinder in a direction opposite to the path of the auxiliary exhaust gas to the auxiliary exhaust gas port, the cylinder also having main exhaust gas ports arranged to be opened when the piston approaches the end of its power stroke, means for operating the piston valve, means for forcing a fuel vapor mixture through the intake port, and means for creating suction in the auxiliary exhaust gas port controlled by the piston valve.

6. In a two cycle internal combustion engine including a cylinder, a piston in the cylinder, a crankshaft, and a connecting rod between the piston and the crankshaft; the combination of the head of the cylinder being formed with a valve passage, intake and auxiliary exhaust ports opening into said passage, and a piston valve arranged to open and close said ports, with both

ports being open and closed at the same time, and with said ports arranged so that the intake port is open before the auxiliary exhaust gas port and closed after the auxiliary exhaust gas port closes, the piston valve having a deflector located to deflect the incoming intake charge into the cylinder in a direction opposite to the path of the auxiliary exhaust gas to said auxiliary exhaust passage, the cylinder also having main exhaust gas ports arranged to be opened when the piston approaches the end of its power stroke, intake main exhaust and auxiliary exhaust gas manifolds, the auxiliary exhaust gas pipe from the auxiliary exhaust gas manifold for the auxiliary exhaust gas port in the head of the cylinder being connected to the main exhaust gas pipe and being provided with a nozzle in the main exhaust gas pipe operating to effect suction on the auxiliary exhaust through the auxiliary exhaust gas port in the head of the cylinder, means for operating the piston valve, and means for forcing a fuel vapor mixture through the intake port.
